(57) **CLAIM**

The ornamental design for a motorcycle slider, as shown and described.

DESCRIPTION

FIG. 1 is a top view of the motorcycle slider.

FIG. 2 is a bottom view of the motorcycle slider.

FIG. 3 is a front view of the motorcycle slider.

FIG. 4 is a rear view of the motorcycle slider.

FIG. 5 is a right side view of the motorcycle slider.

FIG. 6 is a left side view of the motorcycle slider; and, FIG. 7 is a top perspective view of the motorcycle slide with phantom lines indicating the environment in which the motorcycle slider is used.

The broken line showing of a wheel in FIG. 7 is for illustrative purposes only and forms no part of the claimed design.

1 Claim, 3 Drawing Sheets
